CLAIM

The ornamental design for a charging panel, as shown and described.

DESCRIPTION

FIG. 1 is a front, right, and bottom perspective view of a charging panel showing our design.

FIG. 2 is a back, left, and bottom perspective view thereof.

FIG. 3 is a front view thereof.

FIG. 4 is a back view thereof.

FIG. 5 is a left view thereof.

FIG. 6 is a right view thereof.

FIG. 7 is a top view thereof; and,

FIG. 8 is a bottom view thereof.

The broken lines in the drawings illustrate portions of the charging panel that form no part of the claimed design.
